United States Patent Office

Des. 178,834
Patented Sept. 25, 1956

178,834

LADY'S HAT OR SIMILAR ARTICLE

Irene Greene, New York, N. Y.

Application January 3, 1956, Serial No. 39,568

Term of patent 14 years

(Cl. D3—13)

Fig. 1

Fig. 2

Fig. 1 is a front perspective view of a lady's hat showing my new design; and

Fig. 2 is a rear perspective thereof.

I claim:

The ornamental design for a lady's hat or similar article, substantially as shown.
